(57) **CLAIM**
The ornamental design for an excavator lip, as shown and described.(51) **LOC (10) Cl.** **15-03**

DESCRIPTION

(52) **U.S. Cl.**

FIG. 1 is a perspective view of an excavator lip showing our new design.

USPC **D15/28; D15/29**

FIG. 2 is top plan view of the excavator lip of FIG. 1.

(58) **Field of Classification Search**

FIG. 3 is a bottom plan view of the excavator lip of FIG. 1.

USPC D15/11, 21, 32, 28, 29, 25; 403/378,

FIG. 4 is a front elevational view of the excavator lip of FIG. 1.

403/379.5, 379; 37/466, 444, 448,

FIG. 5 is a back elevational view of the excavator lip of FIG. 1.

37/450-459, 446, 447, 449, 195;

FIG. 6 is a left side elevational view of the excavator lip of FIG. 1; and,

172/701.3, 772, 772.5, 753, 713

FIG. 7 is a right side elevational view of the excavator lip of FIG. 1.

See application file for complete search history.

The broken lines in the views depict environmental structure that is shown for illustrative purposes only and that does not form any part of the claimed design.
